DESIGN FOR A SEAT

Samuel Kroll and Nathan J. Kroll, Chicago, Ill.

Application September 4, 1934, Serial No. 53,199

Term of patent 7 years

To all whom it may concern:

Be it known that we, SAMUEL KROLL and NATHAN J. KROLL, citizens of the United States, residing at Chicago, in the county of Cook, and State of Illinois, have invented a new, original, and ornamental Design for a Seat, of which the following is a specification, reference being had to the accompanying drawing, forming part thereof, and in which:

Fig. 1 is a top perspective view of a seat showing our design; and

Fig. 2 is a bottom perspective view of the same.

We claim:

The ornamental design for a seat as shown.

SAMUEL KROLL.
NATHAN J. KROLL,
